ABSTRACT: A card initiated actuator comprising a combination of switches preset at either closed or open position for causing operation of a selected actuator when switch positions are reversed by projections on a card acting on respective moving pin tumblers. A switch arm at the exit end of a card slot is tripped by pushing a card against it thereby to start an electric motor which rotates a pair of rollers between which the card is thereby drawn. A second pair of rollers receive the card from the first pair of rollers and mutilate it so that it cannot again be used, before passing it to a collecting box.

CARD ACTUATED SWITCH COMBINATION

Although tumbler locks, frequently called pin tumbler locks, which make use of pin settings adapted to coincide with a shear line, have long been in vogue, development has largely been confined to substantially conventional lock construction. Such departures as have been undertaken to substitute cards, paper tapes or other types of flat objects for the conventional key, have found only modest acceptance which is due in all probability to a combination of factors including limitations in the card or tape itself as a locking or releasing device, as well as limitations in the locking or unlocking structure which make manipulation by card, tape, ribbon or the like undependable, or perhaps which require a relatively expensive tripping mechanism.

It is therefore among the objects of the invention to provide a new and improved card actuated switch combination of such construction that a relatively simple key combination card can be made use of to perform any one of a great assortment of actuating functions.

Another object of the invention is to provide a new and improved card actuated switch mechanism which is simple and positive in its construction and which is of such character that it can be made to operate with relatively simple cards, without prospect of occasional failure.

Still another object of the invention is to provide a new and improved card actuated switch device wherein special mechanism takes possession of the card after it has been inserted in the device and after withdrawing it from reach deposits it in an appropriate inaccessible sealed container.

Still another object of the invention is to provide a new and improved card actuated switch combination wherein, once a card has been used to trigger the switch combination, the card is pulled into the machine and then mutilated or destroyed to such an extent that it can not again be used. With these and other objects in view, the invention consists in the construction, arrangement, and combination of the various parts of the device, whereby the objects contemplated are attained, as hereinafter set forth, pointed out in the appended claims and illustrated in the accompanying drawings.

In the drawings:

FIG. 1 is a perspective view of a typical card adapted for use with the device.

FIG. 2 is a plan view of the device showing the card about to be inserted.

FIG. 3 is a front end elevational view on the line 3-3 of FIG. 2.

FIG. 4 is a fragmentary longitudinal sectional view on the line 4-4 of FIG. 3.

FIG. 5 is a longitudinal sectional view on the line 5-5 of FIG. 2.

FIG. 6 is a fragmentary sectional view showing the card advancing mechanism.

FIG. 7 is a front elevational view of a second form of the device.

FIG. 8 is a fragmentary longitudinal sectional view on the line 8-8 of FIG. 7.

In an embodiment of the invention chosen for the purpose of illustration there is shown a card initiated actuator combination including a frame 10 on the right side of which is mounted an assembly 11 for handling a card 12 and on the left side of which is mounted an electric motor combination 13. The electric motor combination is substantially conventional and includes the electric motor 14 and a gear reduction mechanism 15 which feeds an output or drive shaft 16.

The assembly 11 features an upper plate 20 superimposed over a lower plate 21 forming between them a card slot 22. The card slot has an entrance end 23 and an exit end 24, as indicated in FIG. 2. The upper and lower plates 20 and 21 are supported upon a bed plate 25, a flange 26 of which is bolted to the frame 10 by bolts 27. Screws 28 hold the combined upper and lower plates in position upon the bed plate 25.

On an upper face 30 of the upper plate 20 are mounted three electric trip combination switches 31, 32 and 33, all of which are part of a working circuit (not shown). The precise

number of switches may be varied depending upon what actuating function may be expected of a multiple number of switches in combination. Three have been selected in the present example as being a simple, typical way of making use of the device. Normal position of each respective switch may be either open or closed depending upon the ultimate function which the switches are designed to trip. Naturally, a greater number of switches provides greater opportunity for different combinations. An example is one where different cards like the card 12 may all be so designed as to perform the same function but at different times. Another example is one where different cards keyed differently may be such that the same assembly can be made use of to perform a multiple number of duties.

15 Each switch such as the switch 31, for example, is provided with an arm 34 which is located immediately above its respective pin tumbler bore 35 in which is a vertically reciprocatable pin tumbler 36. Each of these three switches is similarly equipped.

20 The pin tumbler is of such length that it normally extends downwardly into the card slot 22 where it is stopped against the opposite wall of the slot. Lower ends 37 of the pin tumblers are rounded so that they can be shifted in a vertical direction when engaged either by a leading edge 38 of the card 12 or by one of the upwardly extending projections 39 on a corresponding face of the card 12.

25 The projections 39 on one of the cards 12 are so arranged that they will affect the electric switches 31, 32, and 33 in some predetermined specified manner so that when a particular card is inserted into the slot, the condition of the three switches will be set accordingly, either open or closed as the case may be, whereby to cause some appropriate actuator (not shown) to operate in a preconceived fashion.

30 35 Simultaneously with full insertion of the card 12 into the slot, the card is manually pushed against an arm 40 of a starter switch 41 for the electric motor 14, the starter switch 41 being wire connected to the motor 14 in a conventional manner (not shown). Preferably the arm 40 is made yieldable so that after 40 it has been tripped to energize the starter switch 41 it can yield to the passing of the card 12 over it as viewed in FIG. 6, while the motor circuit remains energized.

35 45 When the electric motor 14 is set in operation by closing of the starter switch 41, the motor will operate the gear reduction mechanism 15 causing the output or drive shaft 16 to rotate, thus to rotate a roller shaft extension 42 which carries a series of four sets of annular driving treads 43, 44, 45, and 46, the driving treads being so positioned as to engage an upper face of the card 12 as shown in FIG. 6. An idler shaft 47 is mounted parallel to the shaft extension 42 and journaled in the flange 26 at one side and a similar flange 48 at the opposite side of the bed plate 25.

40 45 In operation a card 12 is inserted into the card slot 22 and pushed as far into it as will bring the leading edge 38 into engagement with the arm 40 of the starter switch 41 at which time the electric motor commences operation as has just been described. At some selected position of the card 12 in the card slot 22, the electric switches 31, 32, and 33 are tripped into a contrary setting so that they will perform the function in combination for which they are set. Meanwhile the roller shaft extension 42 is being operated by the electric motor 14 and takes hold of the card 12, rolling the card between it and idler shaft 47, the idler shaft preferably being provided with a friction gripping tread 49. The motor continues operation for as long as the armature 40 is depressed by the card which is long enough to have the card pulled entirely past the roller shaft extension 42 and the idler shaft 47. After this has happened, the arm 40 is freed and in response to a conventional spring action 50 55 60 65 70 75 80 85 90 95 100 105 110 115 120 125 130 135 140 145 150 155 160 165 170 175 180 185 190 One mutilating roller, as for example, the roller 55 mounted upon a driven shaft 57 may be interconnected to the electric motor 14 or its gear reducer 15 in an appropriate conventional way (not shown) with a delayed action in the starter switch 41 so that the electric motor 14 will continue operation long enough for the mutilating rollers 55 and 56 to pass the card between them and out into the receptacle 51. Teeth, or other appropriate means, are preferably provided on the mutilating rollers to do such damage to the card that it cannot be used a second time in the device. The mutilating roller 56 may be mounted on an idler shaft 58.

It is also conceivable in view of it being possible to use virtually any number of electric switches which may be appropriately called "trip combination switches" to direct actuation of a mechanism in response to a card specifically combined so that by appropriate conventional means the mutilating rollers 55 and 56 may be physically separated from each other, thereby to avoid mutilating that particular card, and then to normally close thereafter for continued mutilation of all other cards.

As mentioned earlier in the description of the device many more trip combination switches than three may be provided depending upon the number of combinations anticipated or the number of different functions which may be expected of different sets of switches.

To still further add to the possible number of electric switches usable in the device, the lower side of the card may also be used as shown in FIG. 8. To accomplish this, a trip combination switch like the switch 60 may be mounted on the underside of the lower plate 21, as shown in FIG. 7. The switch 60 is similarly provided with an arm 61 operable against a pin tumbler 62 in a pin tumbler bore 63, the pin tumbler 62 normally extending into a card slot 22' as shown in FIG. 8. A shoulder or projection 64 on the underside of the card 12 is thus able to shift the position of the pin tumbler 62, thereby to cause a change in the position of the switch 60, for the same or similar purpose already described in connection with the electric switches 31, 32 and 33.

To make room for the switch 60, a specially constructed base plate 25' is used, extending at a substantially lower level than the lower plate 21, and on which the motor switch 41 also

may be mounted.

Having described the invention, what is claimed as new in support of Letters Patent is:

1. An electric actuator adapted to be energized by a card, 5 said actuator comprising a frame having a slot therein having an entrance end and an exit end for reception of the card and a plurality of bores transversely disposed and in communication with said slot, pin tumbler means in said bores normally extending into said slot, an electric trip combination switch in 10 operative engagement with each pin tumbler means, said switches being in a working circuit for performance of a selected function, said card having shoulders thereon at locations corresponding to locations of said pin tumbler means whereby to shift the tumblers and the positions of the respective switches, an electric motor, a card advancing means located adjacent the exit end of said card slot and in driven association with said motor, and a starter switch for said motor intermediate the exit end of said card slot and the card advancing means whereby to effect progress of said card out of 15 the slot after actuation of the trip combination switches.
2. An electric actuator as in claim 1 wherein the shoulders on the card are projections adapted to lift said pin tumbler means.
3. An electric actuator as in claim 1 wherein there are pin 20 tumbler means and respective switches on both sides of the card slot.
4. An electric actuator as in claim 1 wherein there is a collecting area for said cards after they have been released from the advancing means.
- 30 5. An electric actuator as in claim 1 wherein there is a card mutilating means adjacent an exit side of said card advancing means including elements which receive, mutilate and discharge the card.
6. An electric actuator as in claim 5 wherein said card mutilating means comprises a pair of rollers having card defacing elements on the surface of at least one of the rollers.
- 35 7. An electric actuator as in claim 1 wherein said starter switch has a resilient arm extending into a path between the card slot and the card advancing means and said card advancing means is driven by said motor.
